Attorney.*

UNITED STATES PATENT OFFICE.

WILLIAM HODGE, OF EASTON, PENNSYLVANIA.

WASHING-MACHINE.

SPECIFICATION forming part of Letters Patent No. 362,007, dated April 26, 1887.

Application filed December 30, 1886. Serial No. 223,014. (No model.)

To all whom it may concern:

Be it known that I, WILLIAM HODGE, of Easton, in the county of Northampton and State of Pennsylvania, have invented certain new and useful Improvements in Washing-Machines; and I do hereby declare the following to be a full, clear, and exact description of the invention, such as will enable others skilled in the art to which it pertains to make and use ⁵ the same.

My invention relates to washing-machines, and more particularly to that class known as the "cylinder" washing-machine, the object being to provide a device of this character ¹⁵ that will be strong and durable in its construction and efficient in its operation.

The invention further consists in the details of construction and combination of parts hereinafter fully described, and pointed out in the ²⁰ claim.

In the drawings, Figure I represents a side view of my invention with parts cut away to show the interior construction; Fig. II, a plan view. Figs. III and IV illustrate parts in detail.

A represents the tub. Upon each side of the tub A and at opposite points are secured the bearings B B, which support the hollow revolving cylinder C. The bearings B are ³⁰ composed of the straight piece a, which is formed with an offset at a'. The said bearings are secured by staples b upon the sides of the tub A, which embrace the straight portion a. To the under side of the offset a' are arranged the springs b', which bear upon the sides of the tub and regulate the height of the cylinder in relation to the tub. The bearings B are formed at the top with recesses c, in which the shaft of the cylinder rests and is ³⁵ held in place by the straps c'.

The revolving cylinder C is provided with the shaft D, which projects on either side of the cylinder. To the end d of the said shaft is rigidly mounted a spur-gear, E. At any ⁴⁰ point on the periphery of the cylinder I make a section, F, of said cylinder removable and hinge it to the cylinder, and to the inner side of said section F the springs f are attached, each of which is also attached to the cylinder,

thereby forming a sort of spring-flap. To the ⁵⁰ inner side of the cylinder C is arranged a lever, G, whose short end bears against the spring-flap F, affording a means for opening said spring-flap. Openings are made in the sides of the cylinder C, through which the ⁵⁵ lever is operated.

To the side of the tub A, on which the spur-gear E is placed, the upright H is pivoted, said upright being provided at its upper end with a lug, h, which forms a bearing for the ⁶⁰ spur-gear J, secured to the lug h in any suitable manner. The spur-gear J is provided with the handle j, through which the power is applied. The upright H is connected to the bearing B by the spring K, which keeps ⁶⁵ the spur-gears E and J constantly in gear.

At one end of the tub and near the cylinder is arranged the brush L. On each side of the tub are secured brackets l. From said brackets l to the end of the tub the parallel guide-strips m are placed. To each end of the brush L the plates M are secured, provided with the perforations m', which receive the guide-strips m, giving to the brush a uniform backward and forward motion. The brush L is kept in ⁷⁰ contact with the cylinder by means of the springs N, arranged in rear of the brush.

In using my invention I open the spring-flap by means of the lever and insert a portion of the goods to be washed. Then by closing the flap the article is held fast. After having placed the cleansing material in the tub, I apply the power, thereby revolving the cylinder and bringing the goods or articles to be washed in contact with the brush at every ⁷⁵ revolution of the cylinder.

It will be seen by examination of the brush and its spring-connections that it is self-adjusting, and no matter how thick the goods to be washed are the brush will always have ⁸⁰ a firm and steady pressure.

Having fully described my invention, what I claim as new, and desire to secure by Letters Patent, is—

The combination, with the tub A, of a revolving cylinder, C, supported on spring-bearings B B, secured to the sides of the tub, a section, F, of said revolving cylinder made ⁹⁵

removable and provided with a lever, G, for opening and springs f for closing it, a brush, L, sliding on guide-strips, said brush provided with springs N to keep it in engagement with the cylinder C, substantially as described.

In testimony whereof I have signed this

specification in the presence of two subscribing witnesses.

WILLIAM HODGE.
